UNITED STATES PATENT OFFICE

2,484,893

ELECTRIC HEATING UNIT FOR TANKS

Kuno Robert Kuenne, Oconomowoc, Wis., assignor to A. J. Lindemann & Hoverson Company, Milwaukee, Wis., a corporation of Wisconsin

Application October 21, 1947, Serial No. 781,207

10 Claims. (Cl. 219—38)

1

The improvements relate to electric heating devices for hot water tanks, and more particularly to devices adapted to be applied to the exterior of such tanks—usually to upper and lower parts thereof—in the form of a band or girdle surrounding it and insulated from the outer atmosphere by the jacket of non-heat-conducting material with which such tanks are usually provided. They may, however, be used for any purpose to which they may be adaptable.

The primary objects of the improvements are to produce an electric heater of the kind indicated of relatively simple, strong, efficient and durable construction in which all the essential parts are assembled to form a single unitary structure or unit and one which can be quickly and easily applied between the tank and its heat insulating jacket and without any modification of that tank and jacket or the use of any additional structure or any intervening devices of any kind. Other objects and purposes and their advantages will appear from the following specification and the accompanying drawings.

Heretofore it appears to have been the most usual practice to first provide and apply to the shell of the tank a fixed and permanently secured metallic sheath or channel—sometimes called a tunnel—to receive and support in position the electric heating unit and protect it, as well as the outer jacket of the tank, against injury in use and when the said unit is removed for repairs or replacement. This not only adds greatly to the cost of construction in labor and materials but requires rather complicated insulation and non interference provisions between the heating unit, the "tunnel" and the tank, and is attended by other disadvantages, well recognized in the art. Yet no satisfactory construction in which this fixed outer sheath or tunnel has been dispensed with appears to have been produced, although the need for it has long been obvious and many unsatisfactory efforts by those working in the art have been made to supply that need. The primary object of the present improvements is to meet this long felt need and overcome these well recognized disadvantages, and at the same time to provide a more efficient and less costly heating unit for the purpose stated.

In the said drawings, Fig. 1 is a horizontal section of an electric heating unit positioned on a tank, showing an exemplary embodiment of the present invention on line 1—1 of Fig. 4;

Fig. 2 is an inside view of an end portion of the unit before its application to a tank and in the flat;

2

Fig. 3 is an enlarged vertical section substantially on the line 3—3 of Fig. 1;

Fig. 4 is a diagrammatic side view of a tank with upper and lower units applied thereto.

In the drawings, the connections between the resistor and the source of electric current and the thermostat for controlling that current by the desired temperatures have not been shown in detail, as these are old, common and well known in the art. The cylindrical wall or shell of the tank is shown at 1, its inlet pipe at 2 and outlet 3 and its upper cap or cover at 4, while the jacket or layer of heat-insulating material is shown at 5 and its outside sheath of light-gauge sheet metal at 6. The thermostat is indicated at 7 and the connection between the electric resistance heating member and the source of electric current at 8. These may all be of usual and ordinary construction and material and need no further illustration or description. A slight space or clearance between the heat-insulating material and the sides of the heating units is shown at 9.

The elastic heating unit comprises essentially the resistor 10, its supporting insulators 11 and the flexible band 12 with its contractible flange 13 and feet 14 in which the resistor is mounted by means of the insulators.

The band 12 is preferably a strip of light gauge sheet metal, such as aluminum or an aluminum alloy, and is highly flexible and resilient and also highly reflective. Its outer surface is smooth and unbroken so that it will slip through the insulating material with very little friction and will not catch on any irregularities thereof. The flanges 13 are stamped from the same elongated sheet of metal as the band and extend inwardly therefrom at both edges substantially from end to end at an angle of between 90° and 120° to the plane of the band. They are also highly flexible and are provided with numerous spaced V-shaped notches or slits 13' flaring inwardly toward the tank shell, the total maximum width of these notches being about equal to the excess of the circumference of the outer edges of the flanges 13 and band and that of the shell when wrapped around the latter, so that when the heating unit is bent around the shell to form a ring or girdle thereon the said notches will close up the space inside and also give the flanges a substantially continuous, smooth surface to be presented to the insulating material through which they pass.

The flanges 13 are provided along their inner edges with foot flanges 14 turned horizontally and then folded back on themselves as shown at 15 and through which the notches 13' extend, so that

when the unit is applied to the tank shell these notches also will close up approximately and present substantially a smooth continuous surface of the feet to the insulating material jacket and the surface of the tank shell. The folded over portions 15 form sheaths for the reception of flexible metal straps 16 running through them around the unit and provided with end flanges 17 turned outwardly and apertured to receive tension screw bolts 18 whereby the unit is secured on and tightly clamped to the shell after being applied thereto. The end flanges 17 also prevent the straps from pulling through the sheaths of the foot flanges when the unit is being removed and replaced, in the manner hereinafter described.

The insulator holders 11 are positioned in spaced apertures 13" of the opposed flanges 13 located between the notches 13', have enlarged outer bases 19, hook-form inwardly extending portions 20 and recesses 21 in their bases engaging one of the edges of the apertures, so that they may be inserted through said apertures from either side of flange 13 and will maintain their position therein. They are preferably arranged opposite one another, as are also their apertures, but may be in different relation. The resistor 10 is strung on the hook portions 20 of the insulator holders running in zig-zag fashion and out of contact with all other parts around the heating unit. It is preferably a spirally twisted wire and resilient lengthwise as well as laterally and is held in the holders by tension. It also tends to hold the said holders in inwardly extending position in the flange 13 and away from said flange and its band 12.

In use the unit is applied to the hot water tank by wrapping it around the outside thereof and securing the end flanges 17 of the straps 16, and drawing the straps tight by means of the bolts 18. This presses the feet 14 against the outer surface of the tank, binds the unit thereon with the notches 13' substantially closed, so that the flanges and their feet with the band 12 and the wall of the tank form a substantially closed housing and supporting frame for the resistor and the insulators secured therein, except for a small space between the ends of the unit spanned by the bolts 18, which may be closed by insulating material before the space is closed by the cover 22 mounted over an opening in the outer metal jacket which coincides with the space. The outer layer of insulating material 5 is then applied, preferably after the resistor or resistors have been connected with the electric service wiring—through a thermostat or thermostats. The outer light metal wrapping or sheathing 6 is then applied to enclose the heat insulating jacket 5 in the usual manner. If the insulating jacket 5 is of cohesive material it is advisable to first form an annular groove therein slightly larger in cross section than the heating unit and approximating its form so that there will be no fixed engagement between these parts. It will be noted, however, that as the band and its feet are substantially smooth and unbroken and the portions 19 of the insulators which project slightly beyond the flanges 13 are rounded or beveled there will be no engagement between these parts and the jacket.

If it becomes necessary to remove the heating unit from the tank, as for repair or replacement, the bolts 18 are removed and the ends of a plain wire loop secured to the bolt apertures in the turned end flanges 17 of the strap on one side

of the terminal aperture. The unit is then drawn out by pulling on the opposite end of the straps and thus drawing one end of the loop of the plain wire through the annular space between the shell of the tank and its jacket previously occupied by the unit and leaving the other end of the loop projecting out through the end space. Then when the unit is replaced it is only necessary to secure the ends of the straps to the loose ends of the wire which were previously secured thereto and draw the unit back through the annular space left by the removal. This is done by pulling on the opposite and closed end of the wire loop.

10 15 Before restoring the repaired heating unit or a new unit to the tank a coating of semisolid lubricant should be applied to the feet which contact the surface of the tank to reduce the friction between them. It will be found that the unit will 20 slip easily over and around the tank outer wall and through the insulating material, since there are no projecting parts to catch in such material or produce retarding friction, and nothing in the nature of a tunnel or lining is needed. The portions of the insulating holders on the outside of the flange 13 may, however, be countersunk therein if desired.

25 After the heating unit has been positioned on the tank and properly connected the terminal space is preferably filled with loose heat insulating material 23, such as fibreglass, before applying the cover 22, so as to prevent unnecessary loss of heat at that point.

30 35 Various modifications of the details of the exemplary embodiment herein described and shown may be made without departing from the scope and purport of the invention.

What I claim is:

1. In a device of the character described adapted to be positioned between the shell of a hot water tank and a jacket of insulating material surrounding said shell, a girdle-like heating unit in contact with said shell comprising a substantially flat flexible metal band of substantially continuous and unbroken form and of length approximately equal to the horizontal circumference of the shell and adapted to encompass the exterior of the same in spaced relation thereto, integral flanges projecting inwardly along the side edges of said band and adapted to contact said shell and space the band from the shell, said flanges having inwardly flaring notches running through them of a size and form to permit said flanges when bent around the shell to contract progressively inwardly and assume a substantially closed annular form, a series of spaced insulating holders mounted in said flange and extending away from said flanges and band, an electric resistor in communication with a source of electric current strung on and positioned between said insulating holders and spanning the space between the holders on each flange and out of contact with the said band and its flanges and means for connecting and tensioning said band and flange on the shell and securing them thereon, the said elements above recited forming a unitary electric resistance heating member in direct contact with the shell and its insulating jacket but removable therefrom as a unit.

70 2. In a device of the character described adapted to be positioned between the shell of a hot water tank and a jacket of insulating material surrounding said shell, a girdle-like heating unit in contact with said shell comprising a substantially flat flexible metal band of substan-

5 tally continuous and unbroken form and of length approximately equal to the horizontal circumference of the shell and adapted to encompass the exterior of the same in spaced relation thereto, integral flanges projecting inwardly along both side edges of said band having laterally turned foot portions and adapted to contact said shell and space the band from the shell, said flanges and their said feet having a series of inwardly flaring notches running through them of a size and form to permit said flanges when bent around the shell to contract progressively inwardly and assume a substantially closed annular form, a series of spaced insulating holders mounted in said flange and extending away from said flanges and band, an electric resistor in communication with a source of electric current strung on and positioned between said insulating holders and spanning the space between the holders on each flange and out of contact with the said band and its flanges and means for connecting and tensioning said band and flange on the shell and securing them thereon, the said elements above recited forming a unitary electric resistance heating member in direct contact with the shell and its insulating jacket but removable therefrom as a unit.

3. In a device of the character described adapted to be positioned between the shell of a hot water tank and a jacket of insulating material surrounding said shell, a girdle-like heating unit in contact with said shell comprising a substantially flat flexible metal band of substantially continuous and unbroken form and of length approximately equal to the horizontal circumference of the shell and adapted to encompass the exterior of the same in spaced relation thereto, integral flanges projecting inwardly along the side edges of said band and adapted to contact said shell and space the band from the shell, said flanges having inwardly flaring notches running through them of a size and form to permit said flanges when bent around the shell to contract progressively inwardly and assume a substantially closed annular form, said feet being folded over to form a continuous sheaf and a strap-like metallic band in said sheaf extending through the same throughout its length, a series of spaced insulating holders mounted in said flange and extending away from said flanges and band, an electric resistor in communication with a source of electric current strung on and positioned between said insulating holders and spanning the space between the holders on each flange and out of contact with the said band and its flanges and means for connecting and tensioning said band and flange on the shell and securing them thereon, the said elements above recited forming a unitary electric resistance heating member in direct contact with the shell and its insulating jacket but removable therefrom as a unit.

4. In a device of the character described adapted to be positioned between the shell of a hot water tank and a jacket of insulating material surrounding said shell, a girdle-like heating unit in contact with said shell comprising a substantially flat flexible metal band of substantially continuous and unbroken form and of length approximately equal to the horizontal circumference of the shell and adapted to encompass the exterior of the same in spaced relation thereto, integral flanges projecting inwardly along the side edges of said band and adapted to contact said shell and space the band from the shell, said

flange having inwardly flaring notches running through them of a size and form to permit said flanges when bent around the shell to contract progressively inwardly and assume a substantially closed annular form, a series of spaced insulating holders in the form of hooks mounted in said flange and extending away from said flanges and band, said flange being provided with a series of apertures through which said hooks extend inwardly, an electric resistor in communication with a source of electric current strung on and positioned between said insulating holders and spanning the space between the holders on each flange and out of contact with the said band and its flanges and means for connecting and tensioning said band and flange on the shell and securing them thereon, the said elements above recited forming a unitary electric resistance heating member in direct contact with the shell and its insulating jacket but removable therefrom as a unit.

5. In a device of the character described adapted to be positioned between the shell of a hot water tank and a jacket of insulating material surrounding said shell, a girdle-like heating unit in contact with said shell comprising a substantially flat flexible metal band of substantially continuous and unbroken form and of length approximately equal to the horizontal circumference of the shell and adapted to encompass the exterior of the same in spaced relation thereto, integral flanges projecting inwardly along the side edges of said band and adapted to contact said shell and space the band from the shell, said flanges having inwardly flaring notches running through them of a size and form to permit said flanges when bent around the shell to contract progressively inwardly and assume a substantially closed annular form, a series of spaced insulating holders mounted in said flange and extending away from said flanges and band, and said holders being provided with outer bases larger than said apertures, an electric resistor in communication with a source of electric current strung on and positioned between said insulating holders and spanning the space between the holders on each flange and out of contact with the said band and its flanges and means for connecting and tensioning said band and flange on the shell and securing them thereon, the said elements above recited forming a unitary electric resistance heating member in direct contact with the shell and its insulating jacket but removable therefrom as a unit.

6. In a device of the character described adapted to be positioned between the shell of a hot water tank and a jacket of insulating material surrounding said shell, a girdle-like heating unit in contact with said shell comprising a substantially flat flexible metal band of substantially continuous and unbroken form and of length approximately equal to the horizontal circumference of the shell and adapted to encompass the exterior of the same in spaced relation thereto, integral flanges projecting inwardly along the side edges of said band and adapted to contact said shell and space the band from the shell, said flanges having inwardly flaring notches running through them of a size and form to permit said flanges when bent around the shell to contract progressively inwardly and assume a substantially closed annular form, a series of spaced insulating holders mounted in said flange and extending away from said flanges and band, an electric resistor in communication with a source of electric current strung on and positioned between said insulating holders and spanning the space between the holders on each flange and out of contact with the said band and its flanges and means for connecting and tensioning said band and flange on the shell and securing them thereon, the said elements above recited forming a unitary electric resistance heating member in direct contact with the shell and its insulating jacket but removable therefrom as a unit.

of electric current strung on and positioned between said insulating holders, said resistor being spiral in form and lengthwise stretchable and spanning the space between the holders on each flange and out of contact with the said band and its flanges and means for connecting and tensioning said band and flange on the shell and securing them thereon, the said elements above recited forming a unitary electric resistance heating member in direct contact with the shell and its insulating jacket but removable therefrom as a unit.

7. In a device of the character described adapted to be positioned between the shell of a hot water tank and a jacket of insulating material surrounding said shell, a girdle-like heating unit in contact with said shell comprising a substantially flat flexible band of substantially continuous and unbroken form and of length approximately equal to the horizontal circumference of the shell and adapted to encompass the exterior of the same in spaced relation thereto, integral flanges projecting inwardly along the side edges of said band and adapted to contact said shell and space the band from the shell, said flanges having inwardly flaring notches running through them of a size and form to permit said flanges when bent around the shell to contract progressively inwardly and assume a substantially closed annular form, a series of spaced insulating holders mounted in said flange and extending away from said flanges and band, an electric resistor in communication with a source of electric current strung on and positioned between said insulating holders and spanning the space between the holders on each flange and out of contact with the said band and its flanges and means for connecting and tensioning said band and flange on the shell and securing them thereon comprising bent inwardly extending vertical flanges at the ends of said band flanges and a contractible connecting member engaging said vertical flanges, the said elements above recited forming a unitary electric resistance heating member in direct contact with the shell and its insulating jacket but removable therefrom as a unit.

8. In a device of the character described adapted to be positioned between the shell of a hot water tank and a jacket of insulating material surrounding said shell, a girdle-like heating unit in contact with said shell comprising a substantially flat flexible metal band of substantially continuous and unbroken form and of length approximately equal to the horizontal circumference of the shell and adapted to encompass the exterior of the same in spaced relation thereto, integral flanges projecting inwardly along the side edges of said band and adapted to contact said shell and space the band from the shell, said flanges having inwardly flaring notches running through them of a size and form to permit said flanges when bent around the shell to contract progressively inwardly and assume a substantially closed annular form, a series of spaced insulating holders mounted in said flange and extending away from said flanges and band, an electric resistor in communication with a source of electric current strung on and positioned between said insulating holders and spanning the space between the holders on each flange and out of contact with the said band and its flanges and means for con-

necting and tensioning said band and flange on the shell and securing them thereon, the said elements above recited forming a unitary electric resistance heating member in direct contact with the shell and partly with its insulating jacket but removable therefrom and insertible between them as a unit by sliding said unit through an annular clear space between the said shell and insulating jacket.

9. In a device of the character described, a girdle-like heating unit adapted to be passed around and positioned in close contact with the shell of a hot water boiler, said heating unit comprising a flat imperforate metal band, integral flanges extending inwardly from said band throughout its length and integral feet flanges extending laterally therefrom and in contact with said shell, and a resistor extending through said band and its flanges from side to side and from end to end mounted therein and united therewith but in spaced relation thereto and to said metal band, said flanges having numerous outwardly flaring slits therein and extending laterally therethrough, the total width of the extremities of said slits being approximately equal to the difference in length between the circumference of the band and the circumference of the foot flanges, whereby when said unit is positioned around the shell of a tank the said slits will be substantially closed and will present in effect closed up surfaces.

10. In a device of the character described, a girdle-like heating unit adapted to be passed around and positioned in close contact with the shell of a hot water boiler, said heating unit comprising a flat imperforate metal band, integral flanges extending inwardly from said band throughout its length and integral feet flanges extending laterally therefrom and in contact with said shell, and a resistor extending through said band and its flanges from side to side and from end to end mounted therein and united therewith but in spaced relation thereto and to said metal band, said flanges having numerous outwardly flaring slits therein and extending laterally therethrough, the total width of the extremities of said slits being approximately equal to the difference in length between the circumference of the band and the circumference of the foot flanges, whereby when said unit is positioned around the shell of a tank the said slits will be substantially closed and will present in effect closed up surfaces, said unit adapted to be inserted between a tank shell and its exterior lining of insulating material and to be passed around the tank between them without the intervention of any means for preventing contact between the unit and said jacket.
